O REDMOND.

Steam Plow.

No. 59,073.

Owen Redmond

UNITED STATES PATENT OFFICE.

OWEN REDMOND, OF ROCHESTER, NEW YORK.

IMPROVEMENT IN STEAM-PLOWS.

Specification forming part of Letters Patent No. 59,073, dated October 23, 1866.

To all whom it may concern:

Be it known that I, OWEN REDMOND, of Rochester, county of Monroe, and State of New York, have invented a new and useful Improvement on Steam-Plows, of which the following is a full and exact description, reference being had to the annexed drawings, making part of this specification.

I am aware that several efforts have from time to time been made to construct such a steam-plow as would admit of a practical application to the requirements of agriculturists; but hitherto they have proved failures, I think, for want of traction—that is, such a construction of driving wheel or wheels to the machine as will admit of the required steam-power being applied as will draw the plows, without any slipping of those wheels, and at the same time be light and durable.

My invention, therefore, is confined chiefly to the driving or traction wheels of steam-plows. The mode of applying steam as the propeller thereof I leave to the judicious engineer, who can adapt my invention to any of various kinds of small but powerful steam-engines with the necessary effect. The engine could be placed on the frame of traction-wheels.

Figure 1 is a view of the traction-wheel and frame of the machine, no steam-engine being represented thereon; Fig. 2, a plan of the traction-wheel, with the side covering removed, that the interior construction may be readily understood; Fig. 3, plan of lever and movable cam attached; Fig. 4, plan of anchor detached from the wheel.

Wheel A, Fig. 2, is made of cast or wrought iron, five to six feet diameter, having about twelve apertures in the face of its rim, and divided evenly all around. The rim forms a flange ten or more inches wide, and within the apertures an equal number of anchors, B B, are made to enter. The anchors are wedge-shaped, or may be of any other proper design at their outer ends, and fit to move freely in the apertures. Their inner ends are jointed to one end of arms C C, and these arms are fastened at their other ends by studs or bolts to the side of the wheel at D D.

A strong stud is fixed in each anchor at E, and to diminish friction a caster-wheel may be fitted to revolve freely thereon. These

studs pass through slots or openings g in the side of the wheel.

A peculiarly-shaped ring-like eccentric or cam, F, is secured firmly to the main frame of the machine and outside of the wheel. The studs aforesaid rest upon the inner edge of this eccentric. End of lever attached to movable cam, Fig. 3, moves freely on a stud at G, and has a weight suspended to the other end. At a suitable distance from the stud at G there is a hole in the lever, which fits upon a stout bolt or stud in the movable cam H. This cam is curved at its lower edge to conform to the curve of the stationary eccentric F somewhat. The position of the movable cam with respect to that of the eccentric is governed by the lever, and may be so adjusted that while the studs or caster-wheels of the anchors rest upon the edge of the eccentric the edge of the cam will press upon the studs or wheels aforesaid.

The object of the above-described invention is to produce the requisite traction in machinery for drawing steam-plows, &c., by the agency of a series of anchors, which are made to protrude from the margin of the driving-wheels of the machine in such a manner as to penetrate the ground to any suitable depth, and then withdraw up into the wheels again at the proper time.

The operation of the machine is as follows: As the driving-wheels which carry the anchors revolve, the studs or casters move around upon the edge of the eccentric F, and will describe the form of same, whatever that may be, passing in succession under the lower edge of the movable cam H, attached to the lever. The combined form of eccentric F and cam H controls the movement of the anchors in such a manner that as the wheel revolves these anchors are forced out through the rim of the wheel, and are driven into the ground by the weighted lever in a perpendicular manner, or nearly so, and then immediately after they withdraw themselves from the ground in a vertical position upon passing a line somewhat behind the center of the wheel, and thus avoid back-strain upon the anchors and bursting of the ground, which would occur if the anchors did not withdraw at the proper time. The vertical position of the anchors while entering and withdrawing from the soil is produced mainly

by their swinging around upon the arms C C C, and partially by the wedge form of the outer ends of the anchors.

Whenever, in the operation of the machine, a stone or other hard substance should chance to come under an anchor about to enter the ground, in this case the movable cam rises and permits that anchor to rush up into the wheel, and upon passing the obstruction it is pressed into the ground again by the weighted lever.

I may observe that two or four of the above-described traction-wheels would be proper for each machine.

What I claim as my invention, and desire to secure by Letters Patent, is—

1. The anchors, operating substantially as described, or operating them in any manner by which their protrusion and withdrawal are effected in a somewhat similar way.
2. The eccentric F.
3. The movable cam H, lever, and weight, or a spring equivalent to the weight.

OWEN REDMOND.
